UNITED STATES PATENT OFFICE.

SAMUEL SAMPSON, OF NEW YORK, N. Y.

COLLAR-BAR.

1,294,954.

Specification of Letters Patent. Patented Feb. 18, 1919.

Application filed March 14, 1918. Serial No. 222,346.

To all whom it may concern:

Be it known that I, SAMUEL SAMPSON, a citizen of the United States, and a resident of the city of New York, borough of Manhattan, in the county and State of New York, have invented a new and Improved Collar-Bar, of which the following is a full, clear, and exact description.

Among the principal objects which the present invention has in view are: to provide simple means for preventing failure of the meeting ends of a collar to hold the collar firmly; to avoid marring the exposed surfaces of the collar where it is gripped by the bar; and to provide means for holding a necktie in proper position.

Drawings.

Figure 1 is a perspective view of a collar bar constructed and arranged in accordance with the present invention, the same being shown in conjunction with end fragments of a soft collar;

Fig. 2 is a top edge view of the same, the collar ends being shown in section;

Fig. 3 is a front view of the bar, the end fragments of the cover member of the bar being broken away to expose the gripping surface of the inner member of the bar.

As seen in the drawings, the collar bar has two sections indicated in the drawings by the numerals 8 and 9. The said sections are joined by rivets 10 or by other suitable means. The end portions are bowed or sprung, as seen best in Fig. 2 of the drawings, to form resilient gripping end members.

The section 9 has adjacent each end thereof of roughened gripping surfaces 11, upon which are formed a number of spurs or rasp teeth, which are forced into fabric or ma-

terial of the collar by the corresponding pressure ends of the section 8. The grip of the bar on the collar is augmented by the roughened surfaces and whatever wear there is to the fabric occasioned by the roughened surfaces is at the back or in the side of the collar, and therefore less objectionable than if the abrasion occurred at the outside of the collar.

The bar is provided at the middle thereof with a pin hook 12. The hook 12 has a sharpened point adapted for insertion into the fabric of the tie. The purpose of the hook is to support the tie, and thereby avoid the necessity for tightening the tie. Also by supporting the tie adjacent the bottom of the head or knot, the top of the head or knot is thrown forward in a more graceful position than if drawn to a tight grip of the neck.

Claims.

1. A collar bar comprising two resilient bifurcated ends adapted for gripping therebetween the adjacent end sections of a collar; means mounted on one member of said bifurcated ends for frictionally engaging the collar at the inner surface thereof; and means permanently attached to said bar for supporting the weight of a necktie.

2. A collar bar comprising two resilient bifurcated ends adapted for gripping therebetween the adjacent end sections of a collar; means mounted on one member of said bifurcated ends for frictionally engaging the collar at the inner surface thereof; and means permanently attached to said bar for supporting the weight of a necktie, said means embodying an upturned pin hook having a pointed end for penetrating the fabric of the tie.

SAMUEL SAMPSON.
